(57) **CLAIM**

The ornamental design for a vacuum transfer robot, as shown and described.

DESCRIPTION

FIG. 1 is a front, top and right side perspective view of a vacuum transfer robot showing our new design with all arms in a folded state;

FIG. 2 is a front elevational view thereof shown in FIG. 1;

FIG. 3 is a rear elevational view thereof shown in FIG. 1;

FIG. 4 is a top plan view thereof shown in FIG. 1;

FIG. 5 is a bottom plan view thereof shown in FIG. 1;

FIG. 6 is a right side elevational view thereof shown in FIG. 1;

FIG. 7 is a left side elevational view thereof shown in FIG. 1; FIG. 8 is a front, top and right side perspective view of the vacuum transfer robot with the upper arms in an extended state;

FIG. 9 is a front elevational view thereof shown in FIG. 8;

FIG. 10 is a rear elevational view thereof shown in FIG. 8;

FIG. 11 is a top plan view thereof shown in FIG. 8;

FIG. 12 is a bottom plan view thereof shown in FIG. 8;

FIG. 13 is a right side elevational view thereof shown in FIG. 8; and,

FIG. 14 is a left side elevational view thereof shown in FIG. 8.
